Patented June 8, 1915.

UNITED STATES PATENT OFFICE.

GEORGE S. HILTZ, OF NEW YORK, N. Y., ASSIGNOR TO STOCK QUOTATION TELEGRAPH COMPANY, OF NEW YORK, N. Y., A CORPORATION OF NEW YORK.

LOCAL-CIRCUIT-CONTROLLING APPARATUS FOR PRINTING-TELEGRAPH SYSTEMS.

1,142,037.

Specification of Letters Patent.

Patented June 8, 1915.

Application filed September 8, 1914. Serial No. 860,593.

To all whom it may concern:

Be it known that I, GEORGE S. HILTZ, a citizen of the United States, residing in the borough of Brooklyn and county of Kings, 5 in the city and State of New York, have invented certain new and useful Improvements in Local-Circuit-Controlling Apparatus for Printing-Telegraph Systems, of which the following is a full, clear, and ex- 10 act description.

In printing telegraph systems in which a number of receiving instruments are controlled by the same transmitter, as in the case of stock-tickers, news-tickers, and the 15 like, it is customary to put the receivers in one or more local circuits and to control the latter through one or more relays. In modern systems, particularly those operating on a single main-line circuit, the current 20 is essentially alternating, that is, it consists of a series of impulses alternating in polarity. For this reason the relay is in effect a pole-changing switch, actuated electromagnetically by the main line current.

25 Hence breaking of the main-line circuit does not open the local circuit but leaves current flowing in the latter in the same direction as the last impulse in the main line; so that when the main line current is cut off at the 30 close of business a further operation of some sort, as for example the opening of a manually actuated switch, is necessary if the current of the local circuit is also to be cut off. This duty is often overlooked or forgotten 35 by the operator or attendant with the result that the local circuit or circuits remain closed, with consequent waste of current and other disadvantages.

40 I have accordingly been led to devise my present invention, which has for its chief object to provide an improved system of control for the local circuit or circuits, by which the opening of the main circuit for more than a momentary period of time will 45 cause the former to be opened also.

A further object is to provide a system in which the closing of the main circuit for sending will simultaneously close the local 50 circuit or circuits controlled thereby. Inasmuch as in most cases the main circuit is open when not in use, being closed by the mere act of depressing a transmitter key and opened by release of the key, it will be seen that when the invention is employed 55 with such a system the local circuit will be

closed only so long as the operator is actually using the line.

To these and other ends the invention consists in the novel features of construction and combinations of elements hereinafter described. 60

Of the various embodiments of which the invention is capable I have selected for illustration and specific description herein the one which at the present time is believed to exhibit the invention in its most convenient and effective form. This embodiment is illustrated diagrammatically in the accompanying drawing; to which reference is now made. Two local circuits are shown, each 65 with controlling devices, but it is to be understood that the precise number, whether one or two, or more, is immaterial. The two illustrated are equipped exactly alike, so that a description of one will suffice for 70 both. 75

In the embodiment illustrated the specific construction of the transmitter is immaterial, so long as it is adapted to send impulses of alternating polarity. Usually the 80 transmitter is semi-automatic in character, the depression of a key serving to send to the line the number of impulses corresponding to the letter or character which it is desired to print. 85

In the drawing I have shown at A a simple transmitting device, the same consisting of two conducting bars 10, 11, and two keys 12, 13, playing between the bars and normally in contact with the upper bar only. The direct-current source 14 being connected to the bars as shown, it will be seen that if key 12 is depressed out of contact with the upper bar and into contact with the lower an impulse will be sent over the line in one 95 direction, as for example that indicated by the arrow α . Depression of the other key will therefore send an impulse in the opposite direction, indicated by the arrow α' . 100

The relay B, which controls the local circuit at the left of the drawing, consists of two magnets, b , b' , each having an inner winding 15 and an outer winding 16, the former being shown as composed of coarser wire to distinguish it readily from the outer winding. The inner windings, which are in series with each other and with a direct-current source 17 through a pair of separable contacts 18, 19, are so disposed as to produce poles of the same strength and the 110

same sign, for example, positive, at the inner ends of the cores 20, 21 when the current is flowing from the source 17. Hence so far as these fields are concerned there is 5 no tendency for the pivoted armature or tongue 22 to swing one way or the other. The result is that in the absence of any other magnetization the tongue will cling to whichever of the contacts 23, 24 it was 10 last brought. On the other hand, the outer windings 16, which are in series with each other and with the transmitter A, are so disposed as to produce poles of unlike sign at the inner ends of the cores, for example 15 positive in the core 21 and negative in the other when a positive impulse is flowing. The positive field thus produced will then strengthen the positive field at the end of core 21 due to the winding 15 around the 20 core, but the negative field at the other side will neutralize or greatly diminish the positive field already existing there, and in consequence the armature will be powerfully attracted toward the right. Similarly, the 25 armature is attracted toward the left when the main-line current is reversed. In this way a comparatively weak line-current suffices to produce very rapid movement of the relay armature. As shown, the positive 30 terminal 24 is connected by wire 25 to the positive pole and the negative terminal 23 is connected to the negative pole of the local battery 26. The battery is "split" centrally and grounded at 27. The contact 35 18, in circuit with the source 17 and the windings 15, is stationary, while the contact 19 is carried by one end of a pivoted contact-lever 29. A light coil spring 30 tends to close the contacts, but the adjacent end 40 of the lever bears on an armature 31 which is urged clockwise by a stiffer spring 32, so that when the armature is in the position shown the contacts 18, 19 are open.

The local circuit through the receiving instruments, indicated diagrammatically at R, R', is completed from the armature or tongue 22 through wire 22^a and a pivoted contact lever 33 carrying a contact 34, and a stationary contact 35, which latter is connected 45 to one side of the receivers by the wire 36. On the opposite side the local circuit is grounded at 37. The lower end of the lever 33 bears on the adjacent end of the armature 31, and is urged clockwise, tending to close 50 the contacts 34, 35, by a light spring 38. It will be understood that the spring 32 is 55 stronger than springs 30 and 38 combined, so as to hold contacts 18-19 and 34-35 open.

60 The armature 31 is actuated by two magnets 39, 40, the cores of which are preferably laminated or composed of bundles of wire, as indicated. The two magnets mentioned are in series with each other and with the 65 transmitter A through the outer windings

16 of the relay or repeater B. These magnets are so designed as to their time-constants that when an alternating line current of the minimum or any higher frequency used is flowing through them they will swing 70 the armature 31 to the left and hold it there firmly, thereby allowing the springs 30 and 38 to close the contacts 18-19, 34-35, and hold them closed.

In the system illustrated, the time constants of the magnets 39, 40 of the local-circuit-controlling device C should be rather short, and, if necessary, the spring 32 rather sluggish, to insure that when the current is reversed the consequent reversal of the polarities of the magnets will be quick enough to cause the magnets to "pick up" the armature and hold it in the closed position before the spring has had time to act. For this purpose the residual magnetism of the cores should be rather small, and accordingly I prefer to make the cores of wires or laminæ, as indicated. It is in general desirable to have the magnets as quick-acting as possible, as it permits the use of a spring 32 strong enough to swing the armature clockwise with certainty when the main-line circuit is opened at the close of business and yet not strong enough to allow "chattering" while the alternating current is flowing.

The local circuit of the receivers R', R', at the right-hand side of the drawing, is equipped like the one already described. Thus the local circuit of the relay D through the source 41 and the inner windings (not shown) of the relay magnets is closed, when the system is in operation, through the contacts 42, 43, thereby impressing on the cores a magnetization of constant polarity; while the outer windings of these relay magnets, grounded at 55, are in series with the transmitter and with the similar windings of the magnets of relay B. Similarly, the positive terminal 44 is connected with the positive pole of the local battery 45, whose other pole is connected to the terminal 47; the battery being "split" and connected to ground at 48. The armature or tongue 49 is connected by wire 50 to one side of receivers R' through the contact lever 51 and the contacts 52, 53, and on the other side of the receivers is grounded at 54. The magnets of the controlling device E, which is in all respects similar to the device C, are in the main line, in series with the magnets of the latter device, and the main line is grounded at 56.

In order to make the various circuits perfectly clear they may be traced as follows: When the key 12 is depressed, the current flows from battery 14 to bar 11, key 12, magnets 57-58 and 40-39, wire 59, outer windings of the relays B and D, and thence through wire 60 to ground 55. This current energizes the aforesaid magnets, where-

upon the contacts 18-19, 34-35, 42-43, and 52-53 are closed. Current then flows from the battery 17 through the inner windings of the relay B and through wire 61, lever 29, and contacts 19-18 back to the battery. At the same time, the armature 22 is swung to the right, so that current flows from the battery 26 through wire 25 to terminal 24, armature 22, wire 22, lever 33, contacts 34-35, wire 36, through the receivers R to ground 37, thence to ground 27 and back to the battery 26. Currents in the same direction also flow through the corresponding circuits at the right, through the contacts 42-43, and through the armature 49 and contacts 52-53 to the receivers R' and ground 54. Upon depression of the key 13 the current in the main line, through the controllers C, E, and relays B, D, is reversed,—but without causing the contacts 18-19, 34-35, 42-43, and 52-53 to open. The armatures 22 and 49, however, swing to the left, so that in the left-hand receiver-circuit the direction of the current is now from battery 26 to ground 27, ground 37, receivers R, wire 36, contacts 35-34, lever 33, wire 22, armature 22, terminal 23, and wire 62 to the battery; while in the right hand circuit it flows in the corresponding direction and path, namely, from battery 45 to ground 48, ground 54, receivers R', contacts 53-52, lever 51, wire 50, armature 49, terminal 47, and wire 63 back to the battery.

It will thus be seen that when impulses of rapidly alternating polarity are being sent through the controlling magnets 40-39, 57-58, the receiving local circuits and the relay magnetizing circuits (through the inner windings) are kept closed by the controlling magnets; so, also, if a current of constant polarity, or a prolonged impulse is sent over the line, as for example to actuate the printing devices of the receivers after such devices have been "set up" by the alternating impulses. On the other hand, a break in the main-line circuit of more than momentary duration, as when the line is opened at the close of business for the day, deenergizes the controlling magnets and permits their spring-actuated armature to open the relay and receiver circuits, thereby leaving all parts of the system dead. The first impulse thereafter, however, closes the circuits mentioned and restores the system to operative condition.

It is to be understood that the invention is not limited to the specific arrangement and construction herein illustrated and described but can be embodied in other forms without departure from its proper spirit and scope.

I claim:

1. The combination with one or more receivers, of a local circuit therefor, a relay connected with the local circuit to control the same, a relay-circuit to magnetize the

relay, a main-line circuit through the relay to actuate the same in conjunction with the magnetization produced by the relay-circuit, an electromagnetic controlling device in the main-line circuit, and means actuated by said device to keep the local circuit and the relay circuit closed when the main-line circuit is closed and operating automatically to open the local circuit and the relay circuit when the main-line circuit is opened, as set forth.

2. The combination of a relay having a local energizing circuit, a main-line circuit through the relay to additionally energize the relay, one or more receivers having a local energizing circuit controlled by the relay, an electromagnet in the main-line circuit and energized by current therein, an armature in the field of the electromagnet, and means actuated by the armature to keep the receiver and relay circuits closed when current is flowing in the main-line circuit and to keep the same open when the main-line circuit is open.

3. The combination with a main transmitting-circuit, of a relay therein having a local energizing circuit, one or more receivers having a local circuit controlled by the relay, and automatic means under the control of the main transmitting circuit to open and close both said local circuits.

4. The combination with a main transmitting circuit, and means therein for sending current impulses of alternating polarity in said circuit, of a pole-changing relay in the main transmitting circuit, one or more receivers having a local circuit controlled by the relay to receive current impulses in predetermined correspondence with current impulses in the transmitting circuit, and automatic means controlled by the transmitting circuit to open and close the local circuit.

5. The combination with a main transmitting circuit, of a pole-changing relay therein, one or more receivers having a local circuit connected with the relay to receive alternating current-impulses in predetermined correspondence with the current impulses in the main transmitting circuit, and automatic means to open the local circuit when the main transmitting circuit is dead.

6. The combination with a main-line circuit, and means for sending current-impulses of alternating polarity therethrough, of a pole-changing relay in said circuit, one or more receivers having a local circuit connected with the relay to receive alternating current-impulses in predetermined correspondence with the impulses in the main-line circuit, and means operating automatically to open the local circuit when the main-line circuit is dead, and adapted to keep the same closed when the main line circuit is alive.

7. The combination with a main-line cir-

4

cuit, and means for transmitting there-through current impulses of alternating polarity, of a pole changing relay in said circuit for actuation thereby and having a local direct-current energizing circuit, one or more receivers having a local circuit connected with the relay to receive current impulses of alternating polarity in predetermined correspondence with the impulses in the main-line circuit, and automatic means controlled by the main-line circuit to open and close both said local circuits.

8. The combination with a main-line circuit for alternating current-impulses; of a pole-changing relay comprised of a pair of oppositely disposed magnets having a local circuit to produce like poles at the inner ends of the magnets, windings in series with the main-line circuit to produce unlike poles at 20 said inner ends, an armature between the magnets, and contacts on opposite sides of the armature; a source of direct current having its terminals connected with the relay contacts; one or more receivers connected with the armature and with the said source between the terminals thereof; and means controlled by current in the main-line circuit to keep closed the relay local circuit and the connection between the receivers and the relay armature.

9. The combination with a main-line circuit for current-impulses of alternating polarity; of a relay in said circuit; one or more receivers having a local circuit controlled by the relay in predetermined correspondence with the current impulses in the main-line circuit; and means to keep the local circuit closed when the main line circuit is alive and to open the local circuit when the 50 main-line circuit is dead, said means including an electromagnet connected in the main-line circuit and adapted to be energized substantially continuously by the current impulses therein.

10. The combination with a main transmitting circuit; of one or more receivers, having a local circuit; a relay in the transmitting circuit and controlling the local circuit; separable contacts in the local circuit; a spring actuated lever to close the local circuit at the contacts; an electromagnet in the transmitting circuit; and a spring-actuated armature for the electromagnet, coöperating with the said lever to actuate the same and hold the local circuit open when the electromagnet is deenergized and to permit the lever to close the local circuit when the electromagnet is energized.

11. The combination with a main circuit

and means for transmitting current-impulses 60 of alternating polarity thereover; of a relay in the main circuit; one or more receivers having a local circuit controlled by the relay; contacts in the local circuit; a lever to shift one of the contacts into and out of engagement with the other; a spring connected with the lever to swing the same in one direction and thereby close the local circuit at the contacts; an armature engaging the lever; a spring connected with the 70 armature to swing the armature and rock said lever against the tension of its spring to open the local circuit at the contacts; and an electromagnet in the main circuit and adapted to be continuously energized by the 75 current-impulses therein to swing the armature against the tension of its spring and thereby permit the first-named spring to act.

12. The combination with a main circuit, and means for transmitting alternating current-impulses thereover; of a pole-changing relay in series with the main circuit and having a local energizing circuit; separable contacts in the said relay-energizing circuit; a lever to close the contacts; a spring to 80 actuate the lever; one or more receivers, having a local circuit controlled by the pole-changing relay whereby the current-impulses in the main circuit are repeated in the local receiver-circuit; separable contacts in the 85 receiver-circuit; a lever to close the last named contacts; a spring to actuate the last-named lever; an armature pivoted between its ends and having its ends in engagement with said levers; a spring connected with the armature to swing the same in opposition to the lever-springs and thereby open the local circuit of the receivers and the relay energizing circuit; and electromagnets in the main circuit and adapted to be continuously energized by the alternating current-impulses therein, one of said electromagnets being arranged adjacent to one arm 90 of the armature and on one side thereof and another adjacent to the other arm of the 95 armature on the other side thereof, whereby both magnets when energized act to swing the armature in the same angular direction against the tension of its spring to permit the springs of said levers to act and close the 100 local circuits.

In testimony whereof I affix my signature in the presence of two subscribing witnesses.
